GUY P. THURBER, OF PITTSBURGH, PENNSYLVANIA.

AUTOMATIC TRAIN-CONTROLLING SYSTEM.

1,217,530.

Specification of Letters Patent. Patented Feb. 27, 1917.

Application filed November 1, 1912, Serial No. 729,086. Renewed July 26, 1916. Serial No. 111,542.

To all whom it may concern:

Be it known that I, GUY P. THURBER, a citizen of the United States, and a resident of Pittsburgh, in the county of Allegheny and State of Pennsylvania, have invented 5 certain new and useful Improvements in Automatic Train-Controlling Systems, of which the following is a specification.

This invention relates to those systems of 10 automatic train control wherein certain controlling devices carried by the train, act in the event of danger or like conditions which the system is capable of detecting, to bring the train under automatic control and either 15 stop it or govern its movement in some way. Such systems usually operate upon the normally closed electric circuit principle, so that if for any reason the circuit is ruptured or similarly affected, the train will be placed 20 under automatic control. And the actual control is usually exercised by using the brake system with which the train is ordinarily equipped. The automatic controlling mechanism therefore usually consists of a 25 device or devices having connection with the fluid circuit of the air or other fluid pressure brake system, and actuated when the electric circuit is broken to act upon the brake system to cause an application of the 30 brakes. After such an automatic application of the brakes it is necessary in order to release the brakes and restore normal running conditions, to again restore the electric circuit. Such means have heretofore been 35 provided in the form of a manually operated key or switch which when operated would complete an energizing and restoring circuit through the electrically controlled devices. It is necessary in the practical operation 40 of systems of this character to provide some means whereby the automatic control may be rendered inoperative, so that if it becomes necessary, as in the case of an accident in the system, the whole of the automatic 45 controlling system may be simply disconnected and rendered inoperative. One of the objects of my invention is to provide in a single device, a means whereby in the one instance the controlling circuit can be restored, or by which in the second instance 50 the automatic controlling system may be rendered inoperative. This object I accomplish by means of what I term a "cut-out valve," which valve is interposed in the fluid pressure connections between the brake sys-

tem and the automatic controlling devices, and electrically connected with the automatic controlling devices, and which is so constructed that it will in one position establish an energizing circuit through such 60 automatic controlling devices, and will in another position entirely disconnect the automatic controlling devices from the brake system.

In the most common type of braking systems, the brakes are applied by releasing the air—so in a case like this, the automatic controlling devices will be arranged so as to release the air when the electric circuit is ruptured. To conserve and prevent undue 65 waste of the air under pressure, another feature of the invention consists in arranging the cut-out valve so that it will during the movement of reenergizing and restoring 70 the electrically governed controlling devices, cut off the further escape of the air.

My invention contemplates also the provision of means for indicating to the engineer or motorman whether or not the automatic controlling system is operative. In 80 this way the engineer or motorman may know whether or not he can rely upon the automatic control system. This indicating means I preferably place under the control of the cut-out valve and arrange it to indicate the operativeness of the automatic control system so long as the cut-out valve is in either the running or the restoring positions, and to indicate the inoperativeness of 85 the control system when the cut-out valve has been operated to cut out the automatic control. The indicating means may simply be a signal lamp in the cab, controlled by a circuit which is carried to the cut-out valve and there governed according to the 90 different positions of such valve.

Various other objects and features of the invention will appear as the specification proceeds.

In the accompanying drawings I have 100 shown the invention in a concrete and preferred embodiment but I would have it understood that various changes in the arrangement and construction of the parts 105 may be made without departing from the spirit and scope of the invention.

In the drawings:

Figure 1 is a general and more or less 110 diagrammatic view of an automatic train control system embodying the invention.

Fig. 2 is a transverse sectional view of the cut-out valve taken substantially on the line 2—2 of Fig. 4.

Fig. 3 is a broken detail view of one of the switch terminals.

Fig. 4 is a longitudinal sectional view of the cut-out valve.

Figs. 5, 6 and 7 are transverse sectional views of the same taken substantially on lines 5—5 of Fig. 4, showing first the valve in its normal or running position, second, the valve in the restoring position, and third the valve in the cut-out position with the automatic control system rendered inoperative.

Like reference characters refer to corresponding parts throughout the several views.

I will outline first the general operation of the automatic train control system which I have illustrated: This system includes as one of its principal elements, a normally closed and charged partial electric circuit carried on the train, which is dependent for its completion upon the traffic rails, and which circuit includes within it certain electrical devices for controlling the operation of the train. This so-called cab or train circuit is carried to the track rails by way of two separated contact devices such as two trucks or sets of trucks which are insulated from each other. Thus in the drawings one leg 10 of the train circuit extends to a truck 11 on the locomotive while the other leg 12 of the circuit extends to a truck or the two trucks 13 of the tender. The two sets of trucks are insulated from each other in the present instance by insulating the trucks of the tender from the body of the tender, as by means of suitable insulation 14. The device which is directly responsive to the condition of this circuit is here shown as a relay 15. A source 16 of electrical energy is included in the partial train circuit for normally energizing the relay. It will be seen that when the rails are uninterrupted, the flow of current will be from the source (here shown as a battery) through the leg 10 and truck 11 to the rails 17, thence along the rails and up through insulated trucks 13 and the other leg 12, back to the source. The relay 15 is energized by this flow of current, it being shown as connected direct to the leg 12. If any break should occur in the rails this circuit would be rendered incomplete and hence the relay would become deenergized. To insure a positive break in this circuit and to prevent the circuit, once it is broken, from restoring itself, a part of the circuit is preferably, as by means of a front connection 18, led through the armature 19 controlled by the relay. And to detect any breakdown in the truck insulation the conductor 20 which leads back to the return side of the battery, may be connected to detector plates 21 interposed in

the insulation of each insulated truck. Also when, as in the case shown, the insulated trucks are to be insulated from the balance of the train, the return conductor 20 may be led through a detector plate 22 interposed in the coupling insulation 23. It is by controlling the completion of this train circuit that the train is controlled. For this purpose the rails are made of higher resistance or rendered electrically discontinuous at certain points, as by the insertion of suitable insulation 24, and an artificial shunt is provided around this insulation, which shunt may be broken so as to rupture the train circuit when the train is passing over an insulated joint. This shunt or "jumper circuit", as it has been called, consists of a conductor 25 extending from the end of one insulated rail to the end of the adjoining insulated rail. And this shunt has interposed in it a switch or circuit closing member 26 which is controlled to open or close the jumper circuit. The shunt is controlled in the present instance by a magnet 27 having conductors 28 extending from a block 29 station or other source of control.

The cab or train relay 15 may be used to directly control the train controlling device or devices, or it may be utilized simply as a relay to control circuits through such electrically governed train controlling devices. In the illustration, it is utilized in this latter capacity, it having for that purpose armatures 29 which form a part of a circuit 30 through a so-called magnet valve 31. This magnet valve is energized from a suitable source, such as a cab battery 32. The energizing circuit for the magnet valve will be seen to be by way of conductors 33 and 34 to the upper one of the armatures 29, conductor 30 to the magnet valve, and by the other conductor 30, lower armature 29 and conductors 35—36 back to the other side of the battery 32.

The function of the magnet valve is in the present instance to control passage of an actuating fluid to the automatic brake valve 37, so a pipe connection 38 is therefore provided between the magnet valve and the automatic brake valve. The supply of fluid under pressure for operating the automatic brake valve is taken from a suitable source, the same being here the train pipe 39, with which the magnet valve is connected by pipes 40 and 41. In its general construction the magnet valve consists of a magnet winding 42, which serves when energized to attract an armature 43, said armature operating a stem 44, carrying inlet and exhaust valves 45 and 46 respectively. When the magnet valve is energized, as in the illustration, the inlet valve will be open and fluid under pressure will therefore pass from the train line through pipes 41 and 40 past the open inlet valve and through passage 47 to

into the pipe 38 leading to the automatic brake valve. The fluid under pressure thus conducted to the automatic brake valve, acts upon the head of a piston 48, which piston 5 serves when so acted upon to hold the train exhaust valve 49, closed. This train exhaust valve is in communication with the train line by pipes 50 and 41.

Ordinarily the train is controlled in the usual way by means of an engineer's brake valve 51, which is connected with the train pipe by a connection 52. When a danger or like condition exists the train is brought under automatic control. Thus for instance 10 when the train encounters a broken jumper circuit (the breaking of which jumper circuit may have been occasioned by the presence of a train in a preceding block) the train circuit can no longer be completed, so 15 20 that the relay 15 becomes deenergized. The deenergization of this relay causes it to drop its armatures, (or armature in case all the contacts are made by the one armature), thus breaking the circuit for the magnet 25 valve. When this latter circuit is broken, the armature 43 of such valve is no longer attracted and a spring 53 or like contrivance shifts the armature so as to close the inlet 30 valve 45 and open exhaust valve 46. The closing of inlet valve 45 prevents any further flow of actuating fluid to the automatic 35 brake valve and the opening of the exhaust valve permits the fluid acting upon piston 48 to escape back through the pipe 38, and 40 passage 47, past the exhaust valve and out through exhaust port 54. Upon the piston being thus relieved of pressure, the spring 45 acts to shift the piston over, thereby opening up the train exhaust valve 49 and permitting the train line pressure to escape by 45 way of such valve. The reduction in pressure thus occasioned in the train pipe causes the setting of the brakes in a well known manner.

45 I will now describe the construction and arrangement of the cut-out valve. This valve is indicated in a general way at 56 in Fig. 1, wherein it is shown, for the purpose of controlling the operativeness of the automatic 50 control devices, interposed in the fluid-pressure connections leading from the train pipe to such devices. While the specific construction of this valve may vary, it consists preferably of a valve casing 57, within which 55 there is rotatably journaled a valve body 58, the two having coöperating ports by which the flow of fluid is governed. Thus in the illustration the valve body has a port 59, which when in register with port 60 in the 60 valve casing permits flow through pipe 50 to the train exhaust valve, and a port 61, which when in register with port 62 in the valve casing permits flow through pipe 40 to the magnet valve. The pipe 41 which 65 conducts the pressure from the train pipe,

preferably enters the valve casing at the bottom (Fig. 4) and the valve body is therefore provided with a longitudinal bore or passage 63 to receive the fluid. To prevent leakage and take up wear, the valve body and its 70 seat are preferably made tapering as shown and a spring 64 may be utilized for holding the valve firmly seated.

Figs. 4 and 5 indicate the valve in its normal or running position. In this position 75 it will be seen that the air or other fluid under pressure flows through pipe 41 into the valve and out through ports 59—60 and 61—62 to the train exhaust valve and magnet valve respectively. In case it is desired 80 to render the automatic control devices inoperative, the valve body is turned around into the position shown in Fig. 7, wherein the ports no longer register and the supply of actuating fluid is thereby cut off from the 85 magnet valve and brake valve.

The cut-off valve may be operated in any suitable manner. In the present instance it is operated manually by means of a suitable key inserted over the angular end 65 90 of the operating stem 66, which is connected to or forms a part of the stem 67 of the valve body.

The circuit closing device by which the cut-out valve is enabled to complete a restoring 95 circuit through the cab relay, is here shown as a segmental contact 68 mounted on an insulating support 69, carried on the valve stem, which when the valve is turned into the restoring position, Fig. 6, forms a 10 bridge between the pair of spring terminals or brushes 70 and 71. The restoring circuit consists of a conductor 72, extending from the brush 70 to the cab relay, and a conductor 73 extending from brush 71, through 10 a source of current to the other terminal of the relay. To save wiring the restoring circuit preferably utilizes a part of the train circuit. Thus, in the illustration, when the valve is turned to the restoring position 11 shown in Fig. 6, a circuit is made from battery 16, through conductor 10 and truck 11 to the track, thence along the track, or across the jumper circuit (25—26) in a case like that illustrated in Fig. 1, to the trucks 13, 1 conductor 12 to the relay, through the relay magnet, and conductor 72, brush 70, contact 68, brush 71, and conductors 73—20 back to other pole of the battery. It will be clear that by this circuit the cab relay will be energized, causing it to pick up its armatures, (or armature, if only the one) and restore the circuit through the magnet valve. In this restoring position of the cut-out valve (Fig. 6) it will be noted that port 59 is no longer in communication with port 60, so that further flow to the train exhaust valve is cut off. But since port 59 is now in communication with port 62, a flow of air will be provided to the magnet valve, so a supply of

air is thus provided to the magnet valve as soon as said valve becomes energized due to the completion of the restoring circuit.

To prevent accidental shifting of the cut-out valve and to cause said valve to automatically return to its normal position when released, I preferably provide means, such as a coiled spring 74, secured at one end 75, to the valve casing and connected with the valve stem so as to exert its force to turn the valve to the normal running position. Means are also preferably provided for limiting the movements of the valve, and for locking the valve in its closed "cut off" position. Such means may be in the form of a stop member 76 movable with the valve body, having a segmental slot 77, in which is engaged the stop pin 78. In the normal running position the end 79, of the slot in the stop member is in engagement with the stop pin (Fig. 5), while the shoulders 80 at or near the opposite end of the slot, by coming into engagement with the stop pin (Fig. 6) normally limit the restoring movement of the valve. For locking purposes the far end of the slot is formed with a locking opening 81, which when the locking pin is in engagement therewith (Fig. 7) serves to lock the valve in the closed position. This locking opening is preferably in connection with the main body of the slot by a narrow neck portion 82, and the locking pin is then formed with a reduced portion 83, which when brought into register with the narrow neck portion will permit the valve to be turned to the cut off position. A spring 84, or like agent, holds the locking pin in its normal position (Fig. 4) with the reduced portion thereof out of line with the reduced neck portion (82) of the locking slot. The locking pin preferably has a stem 85, by which it can be operated.

The complete operation is as follows: When the train encounters a broken rail or a broken jumper between insulated sections of rail, the partial train circuit can no longer be completed. Circuit through the cab relay is therefore broken and the same becomes de-energized and drops its armatures (or armature), thereby breaking circuit through the magnet valve. The magnet valve thus de-energized, releases its armature, and the same is shifted by spring 53 to close inlet valve 45 and open relief valve 46. Further supply of actuating fluid to the piston 48 of the automatic brake valve is thus cut off and the fluid then acting upon the piston is permitted to escape by way of the relief valve 46. Upon release of the pressure upon piston 48, the spring 55 shifts said piston over and opens up train exhaust valve 49. The train line pressure is thus permitted to escape, causing an application of the brakes to be made. If the engineer or motorman sees that the track immediately in

front of him is clear and that he is warranted in going ahead at reduced speed, he may by operating the cut-out valve "pick up" the cab relay and restore normal running conditions. He accordingly in such case applies his key to the stem of the cut-out valve and turns the same to the position shown in Fig. 6. In this position of the valve the contact 68 carried by the valve stem bridges the two terminal brushes 70 and 71, whereby the restoring circuit is completed through the relay. This circuit, as before pointed out, is from battery 16, through conductor 10, truck 11, rails 17, insulated trucks 13, conductor 12, relay 15, conductor 72, brush 70, contact 68, brush 71, conductors 73 and 20, back to the other side of the battery. If the train should have happened to stop with the insulated trucks bridging an insulated joint in the rails, the current instead of flowing along the rails 17 will flow across the jumper which bridges the insulation. The restoration of the circuit through the cab relay energizes the same and it therefore acts to pick up its armatures and again close the circuit through the magnet valve. The magnet valve upon being re-energized acts to close relief valve 46 and again open up inlet valve 45. Further escape of the actuating fluid is thus cut off and a path is again provided for the flow of such fluid to the piston of the automatic brake valve. The turning of the cut-out valve to the restoring position, as shown in Fig. 6, carries the port 59 out of register with the port 60 so that further escape of air from the train line through pipes 41 and 50 is therefore cut off. Also it will be noted in this position that port 59 has been caused to register with the port 62 leading to the magnet valve. Thus in this restoring position of the cut-out valve the restoring circuit is made through the cab relay, further escape of the train line pressure by way of the train exhaust valve 110 is cut off, and flow of the actuating fluid to the magnet valve is provided. The result of this is that any further reduction in the train line pressure is prevented and the actuating fluid is permitted to flow to the magnet valve as soon as the same is energized. The magnet valve being now energized, the actuating fluid flows to the automatic brake valve and acting upon the piston therein causes the train exhaust valve to be closed. The key is withdrawn from the cut-out valve and the spring 74 immediately shifts the same back into the normal running position (Figs. 4 and 5). Conditions have now been restored to normal and the train is therefore free to proceed. If the engineer should desire to cut out the automatic control entirely, he may do so by depressing the stem 85 of the stop pin 78 so as to bring the reduced portion 83 of such pin into register 130

with the reduced neck portion 82 of the slot in the stop member 76. This will permit the valve to be turned around into the position shown in Fig. 7 and at the end of this movement the locking opening 81 will be in line with the stop pin and the spring 84 will then act to shift the stop pin upward with the body of the stop pin engaged in the locking opening, which will thereby lock the valve in this position. It will be noted that in this position all the ports between the valve and the valve casing are out of register and the contact 68 is not in engagement with either of the terminal brushes 70 and 71. The automatic control devices are thus entirely disconnected from the fluid pressure brake system and will therefore have no further effect upon the same.

It is very desirable that the engineer or motorman may know at all times whether or not the automatic control system is in operation and a means for this purpose I have shown in the accompanying illustration as a signal lamp 86 suitably located to be within sight of the engineer and arranged to burn so long as the automatic control system remains operative. In order that the said signal shall indicate when the automatic control system is operative and when it is not, I preferably place the same under the control of the cut-out valve. The cut-out valve is accordingly here shown as provided with an additional pair of terminal brushes 87 and 88 which are arranged to be engaged by a segmental contact 89 movable with the valve body. The circuit for the signal in the present instance is from the battery 32 through conductors 33 and 90 to one side of the signal, through conductor 91, brush 87, contact 89, brush 88 and conductors 92-36 back to the other pole of the battery. The segmental contact 89 is carried by an insulating support 93 on the valve stem and it is of such a length and is so disposed that it will in either of the normal running or the restoring positions make engagement with its coöperating terminal brushes. This feature is clearly shown in Figs. 5 and 6 wherein it will be clear that the circuit through the signal will be complete in either the running or the restoring positions of the cut-out valve. When the cut-out valve is turned to the cut off position shown in Fig. 7, the segmental contact is carried out of engagement with its terminal brushes and the circuit through the signal is thereby ruptured.

The springs or brushes which form the terminals of the restoring and signal circuits may be supported in suitable fashion and the same are here shown as being carried by the binding posts 94, 95, 96 and 97 which are all secured upon a base 98 of insulating material. The wires for these restoring and signal circuits may be carried to

the cut-out valve through conduit 99 which opens into a passage-way 100 extending up into the interior of the valve casing.

To prevent the engineer from acting prematurely in restoring the circuits, I preferentially locate the cut-out valve in such a position upon the train that it will be necessary for the engineer to dismount from his cab before he can reach such valve. This insures that the train shall be brought to a stop or practically so before the engineer can again restore the normal running conditions. In the event of the train ever being brought to a stop with the insulated trucks bridging an open jumper circuit, the train may be permitted to proceed by holding the cut-out valve in the restoring position and at the same time starting up the train to carry the insulated trucks past the insulated joint. In an event of this kind (when the cut-out valve is located in a more or less inaccessible position) the fireman will probably be required to hold the cut-out valve in the restoring position while the engineer runs the train ahead far enough, past the insulated joint. As soon as the insulated joint is passed the train circuit will again be completed through the rails and normal running conditions be restored.

While for purposes of disclosure I have shown and described my invention as applied to the equipment of a steam railway, it will be understood that the invention may be applied equally as well to an electrically propelled railway.

What is claimed, is:

1. The combination with a fluid pressure brake system, of a valve connected therewith for controlling the automatic operation of the brakes, a normally closed electric circuit having means therein for controlling the valve to maintain the brakes inoperative so long as the electric circuit is complete, means for rupturing the circuit to cause application of the brakes, means for restoring the circuit to cause release of the brakes, and means for cutting off the valve from the brake system when the circuit is being restored.

2. The combination with a fluid pressure brake system, of a valve connected therewith for controlling the automatic operation of the brakes, a normally closed electric circuit, a magnet energized by said circuit to control the valve aforesaid to maintain the brakes inoperative so long as the circuit is complete, means for rupturing the circuit to cause application of the brakes, means for completing an energizing circuit through the magnet to cause release of the brakes, and means for disconnecting the valve from the brake system when the magnet is being reenergized.

3. The combination with a fluid pressure brake system, of a magnet valve having com-

munication with the brake system and arranged when deenergized to cause application of the brakes, a normally closed electric circuit for normally energizing the magnet valve, means for rupturing said circuit, means for completing a circuit through the magnet valve to reenergize the same, and means for cutting off communication between the brake system and the magnet valve when reenergizing the latter.

4. The combination with a fluid pressure brake system, of electrically controlled means connected with the fluid pressure circuit of the brake system and arranged when energized to maintain the brakes inoperative, a circuit for normally energizing the said controlling means, an electric circuit including a signal for indicating the existence of the fluid pressure connection between the automatic controlling means and the brake system, means for disconnecting the automatic controlling means from the brake system, means operated by such disconnecting means for establishing an energizing circuit through the controlling means, and means also operated by the disconnecting means when the same is operated to disconnect the automatic controlling means from the brake system, to rupture the circuit through the signal.

5. The combination with a fluid pressure brake system, of electrically controlled means connected with the fluid pressure circuit of said system controlling automatic operation of the same and arranged when energized to maintain the brakes inoperative, a circuit for normally energizing the said automatic controlling means, and a combination cut-out valve and circuit closer adapted to simultaneously disconnect the automatic controlling means from the brake system and to close an energizing circuit through the train controlling means.

6. In combination with the train line of an air brake system, electrically controlled brake-setting mechanism connected with the train line, a circuit for normally energizing said mechanism to maintain the brakes inoperative, and means for temporarily cutting off the brake-setting mechanism from the train line and establishing an energizing circuit through such mechanism.

7. In combination with a fluid pressure brake system, a magnet valve in communication with the fluid pressure circuit of said system and controlling operation of the same, a circuit for normally energizing the magnet valve to maintain the brakes inoperative, a cut-out valve for disconnecting the magnet valve from the brake system, and a switch operated by the cut-out valve in disconnecting the magnet valve from the brake system to establish an energizing circuit through the magnet valve.

8. The combination with a fluid pressure

brake system, of electrically controlled means connected with the fluid pressure circuit of the brake system normally energized to maintain the brakes inoperative and adapted when deenergized to render the brakes operative, a circuit for normally energizing the said controlling means, and a combination cut-out valve and circuit closer interposed in the fluid pressure connection between the automatic train controlling means and the brake system adapted when operated, to temporarily disconnect the automatic controlling means from the brake system and to close an energizing circuit through the said controlling means to re- energize the same.

9. In combination with an air brake system, electrically controlled means connected with the air circuit of the brake system and controlling automatic operation of the brake system, a circuit controlling operation of the automatic controlling means, a combination cut-out valve and circuit closer adapted to temporarily disconnect the automatic train controlling means from the brake system and establish a restoring circuit through the automatic controlling means, or to entirely disconnect the automatic controlling means from the brake system, an electric circuit including a signal for indicating the operativeness of the automatic controlling means, and a switch operated by the cut-out valve to maintain the signal circuit closed when said valve is in the open or restoring positions and to rupture the signal circuit when the valve is operated to entirely disconnect the automatic controlling means from the brake system.

10. In combination with an air brake system, electrically controlled means connected with the air circuit of the brake system and controlling automatic operation of said system, a circuit controlling operation of the automatic controlling means, a combination cut-out valve and circuit closer adapted to temporarily disconnect the automatic controlling means from the brake system and establish a restoring circuit through the automatic controlling means, or to entirely disconnect the automatic controlling means from the brake system, an electric circuit including a signal for indicating the operativeness of the automatic controlling means, a switch operated by the cut-out valve to maintain the signal circuit closed when said valve is in the open or restoring positions and to rupture the signal circuit when the valve is operated to entirely disconnect the automatic controlling means from the brake system, means for normally throwing the cut-out valve to the open position, and means for locking the cut-out valve in closed position.

11. In combination with the train line of a fluid pressure brake system, an automatic

- brake valve connected with the train line to provide escape therefrom and arranged when acted upon by fluid under pressure to cut off escape from the train line, an electrically controlled magnet valve supplied 5 with fluid under pressure from the train line and connected with the automatic brake valve to control the operation of the same, a circuit for normally energizing the magnet valve whereby the same will be actuated to permit flow of fluid under pressure to the automatic brake valve, a cut-out valve for disconnecting the automatic brake valve and the magnet valve from the train line, 10 and a switch operated by the cut-out valve to establish an energizing circuit through the magnet valve.
12. In an automatic train controlling system, the combination with the air brake system of the train, of a relay, a circuit controlled by the relay, a magnet valve in said circuit and connected with the air circuit of said brake system, an automatic brake valve controlled by the magnet valve and connected 15 with the brake system to control the operation of the brakes, and a cut-out device for disconnecting the automatic train controlling system from the brake system and placing the circuit in normal condition.
13. In an automatic train controlling system, the combination with the air brake system of the train, of a relay, a circuit controlled by the relay, a magnet valve in said circuit and connected with the air circuit 20 of the brake system, an automatic brake valve controlled by the magnet valve and connected with the brake system to control the operation of the brakes, a circuit for normally engaging the relay, a cut-out valve 25 for disconnecting the automatic train controlling system from the brake system, and a switch operated by the cut-out valve to complete another energizing circuit through the relay.
14. The combination with a railway train and a fluid pressure brake system carried thereby, of a normally closed charged electric circuit on the train, electrically controlled means in said circuit and connected 30 with the brake system to control the automatic operation of the same when the said circuit is ruptured, and means for disconnecting the automatic controlling means from the brake system and for restoring the circuit after it is broken, the said means located on the train at a point to be reached by the operator only when the train is standing still or approximately so.
15. The combination with a fluid pressure 35 brake system, of electrically controlled means connected with the fluid pressure circuit of the brake system, normally energized to maintain the brakes inoperative and adapted when deenergized to render the brakes operative, a circuit for normally energizing the
- said controlling means, and a combination cut-out valve and circuit closer interposed in the fluid pressure connection between the automatic train controlling means and the brake system and having electrical connection with the electrically controlled means aforesaid, the said cut-out valve being capable of a rotary movement and arranged during such rotary movement to disconnect the automatic controlling means from the 70 brake system and to close an energizing circuit through the electrically controlled means to reenergize the same.
16. In combination with an air brake system, electrically controlled means connected with the air circuit of the brake system and controlling automatic operation of the brake system, a circuit, controlling operation of the automatic controlling means, and a combination cut-out valve and circuit closer interposed between the brake system and the electrically controlled means and having electrical connection with such electrically controlled means, arranged when operated, to disconnect the automatic train controlling means from the brake system and establishing a restoring circuit through the automatic controlling means or to entirely disconnect the automatic controlling means 80 from the brake system.
17. The combination with a railway train and a fluid pressure brake system carried thereby, of a normally closed charged electric circuit on the train, electrically controlled means in said circuit and connected with the brake system to control automatic operation of the same when the said circuit is ruptured, and a device interposed between the automatic controlling means and the brake system and having connection with the electric circuit, adapted to be operated to disconnect the automatic controlling means from the brake system and to restore the electric circuit after it has been broken.
18. In combination with a fluid pressure 95 brake system, an automatic brake valve actuated by fluid under pressure and connected with the fluid circuit of the brake system to control operation of the same, a magnet valve supplied with fluid under pressure 100 and arranged to control flow of such actuating fluid to the automatic brake valve, and a cut-out valve arranged to control flow of actuating fluid to the magnet valve and to control communication between the automatic brake valve and the brake system.
19. In combination with the train pipe of an air brake system, an automatic brake valve actuated by fluid under pressure and connected with the train pipe to control the 115 pressure therein, a magnet valve supplied with fluid under pressure from said train pipe and arranged to control flow of such fluid to the automatic brake valve for actuating the same, and a cut-out valve inter- 120

- posed in the fluid pressure connections from the train pipe to the magnet valve and to the automatic brake valve arranged to control flow of fluid under pressure from the train 5 pipe to the magnet valve and automatic brake valve.
20. In combination with a fluid pressure brake system, a fluid-pressure-actuated automatic brake valve connected with the 10 brake system, said automatic brake valve being inoperative as long as fluid pressure is present, a magnet valve arranged when energized to admit flow of actuating fluid to the automatic brake valve, and a cut-out 15 valve arranged to govern flow of the actuating fluid to the magnet valve and to control the energization of said magnet valve.
21. In combination with a fluid pressure brake system, a fluid-pressure-actuated automatic brake valve connected with the brake 20 system to control operation of the same, a magnet valve controlling flow of actuating fluid to the automatic brake valve, a circuit for energizing the magnet valve, and a cut-out valve arranged to control flow of the actuating fluid to the magnet valve and to cause completion of the circuit through the magnet valve when said circuit has been ruptured.
25. 22. In combination with a fluid pressure brake system, a fluid-pressure-actuated automatic brake valve connected with the brake system to control operation of the same, a magnet valve arranged when energized to 30 permit flow of actuating fluid to the automatic brake valve, a circuit for energizing the magnet valve, a circuit interrupter for rupturing the circuit through the magnet valve, and a combination cut-out valve and 35 circuit restoring device arranged to cut off flow of actuating fluid to the magnet valve and to complete an energizing circuit through the circuit interrupter.
40. 23. In combination with a fluid pressure brake system, an automatic brake valve comprising a train exhaust valve connected with the brake system to control operation of the same and a fluid-pressure-actuated device for operating said train exhaust valve, 45 a magnet valve having inlet and exhaust passages, connections for fluid under pressure to the magnet valve and from the magnet valve to the fluid-pressure-actuated device of the automatic brake valve, the said 50

magnet valve arranged when energized to 55 hold the inlet passage open to permit flow of actuating fluid to the pressure-actuated device of the automatic brake valve and arranged when deenergized to open the exhaust passage therein to permit escape of the 60 actuating fluid from the pressure-actuated device of the automatic brake valve, a circuit for normally energizing the magnet valve, and a combination cut-out valve and 65 circuit restoring device arranged to cut off flow of actuating fluid to the magnet valve and to cause restoration of the magnet valve circuit through the magnet valve.

24. In combination, a fluid brake system, a brake valve for rendering the brake system effective adapted to be held in a normally inoperative position by fluid pressure from the brake system, a normally closed charged electric circuit normally completed through the track, means energized by said 70 circuit for controlling the brake valve and which when deenergized renders the brake valve operative and brake controlling means for reenergizing said circuit.

25. A train controlling system comprising: 75 a normally closed charged electric circuit, a fluid pressure system, a brake valve included in said fluid pressure system and controlled by the electric circuit, a relay in said circuit, means for rupturing said circuit, a cutout 80 valve controlling communication between the fluid pressure system and the brake valve, a single circuit and a signal therein controlled by said cutout valve, a restoring circuit controlled by said cutout valve for closing an 85 other circuit through the relay, means in said cutout valve for cutting off communication between the fluid pressure system and the brake valve, and contacts controlled by said cutout valve, for maintaining the 90 signal circuit closed when the said valve is in normal or in restoring position and for rupturing said signal circuit when said 95 cutout valve closes communication between the fluid pressure system and the brake 100 valve.

Signed at Pittsburgh, in the county of Allegheny and State of Pennsylvania, this 11 day of October, A. D. 1912.

GUY P. THURBER.
